UNITED STATES PATENT OFFICE.

JOHN A. SODERSTROM, OF CHICAGO, ILLINOIS.

NECKTIE.

Application filed February 24, 1920. Serial No. 360,803.

To all whom it may concern:

Be it known that I, JOHN A. SODERSTROM, a citizen of the United States, residing at Chicago, in the county of Cook and State of Illinois, have invented certain new and useful Improvements in Neckties, of which the following is a specification.

The invention relates to neckties which include a clip or foundation upon which the cloth material of the tie is attached and arranged and by which the tie is secured to the collar of the wearer.

The invention is in the nature of an improvement upon neckties of the cross bow variety and upon an improved clip or holder or foundation for use in connection with the same.

It is the primary object of the invention to provide a necktie which shall be attached to and tied upon or arranged upon a clip, holder or foundation quickly detachable from the collar of the wearer and which tie may be adjustable in character in the sense that the cloth portions of the tie making the bow or ascot part may be readily attached to or detached from the foundation or clip, thus making the tie adjustable and the cloth portions thereof interchangeable upon the clip or foundation.

It is a further object of the invention to provide in connection with a detachable clip or foundation for supporting a neck tie an improved construction of tie formed of cloth or other flexible materials adapted to be arranged upon said clip or holder.

It is a further object of the invention to provide certain new and useful improvements in connection with a necktie clip or holder adapting same for detachably supporting the cloth of a bow tie or ascot in such a manner that the cloth will be readily detachable therefrom so that the wearer may conveniently adjust the parts or replace the cloth parts without the necessity of destroying or abandoning the holder or clip. Obviously, this feature of adjustability of the cloth portion of the tie in relation to the clip or holder will increase the normal life of the tie because different portions of the cloth may be adjusted to show most prominently and the cloth may also be reversed to cover or protect worn or soiled portions thereof. Heretofore it has been common to provide, as shown in my prior Patent No. 1,305,947, adjustable spring clips or holders for bow ties similar to that shown in con-

nection with the present invention having the flexible spring member adapted to engage on the outside of the collar tabs when the tie is in position in use, and it has also been common to sew cloth coverings over the exposed extremities of the elastic or spring member of the clip.

It is one of the objects of the present invention to provide improved and economical means for covering the elastic spring member of the clip or holder by means of attaching a wrapper or covering of flexible material thereon and retaining same in position by adhesive means.

It is a further object of the invention to provide in connection with the elastic or spring member of a holder or clip of the described character improved means for attaching the cloth of the tie to the extremities of the elastic or spring member without the necessity of sewing said parts together as has heretofore been common in the art, thus effecting certain economies in manufacture and providing a tie which is completely adjustable and in which the cloth portions may be interchanged without any permanent connections with the metallic holder, clip or foundation.

It is a further object of the invention to provide in a necktie of the described character certain improvements in the manner of arranging the cloth material of a bow tie upon the spring member.

It is a further object of the invention to provide in connection with a metallic spring clip, holder or foundation for bow ties of the described character, comprising a substantially rigid metallic member and a flexible spring member, co-operating elevations and depressions or offset portions in said metallic members adapted to register with each other when the parts are assembled in order to furnish a more secure means for causing the engagement of the holding device, clip or foundation to the tabs of collars and particularly to the tabs of collars where the collars themselves are of a very soft or unstarched material.

It is a further object of the invention to provide in connection with an offset portion on the elastic member of the holder, clip or foundation a slot in said offset portion designed to be formed at the same time as the offset portion and adapted to permit of the insertion of a needle therethrough in sewing a covering or envelope to the spring por-

tion of the clip or for winding or attaching thread thereto when same may be desired in securing the cloth on the clip or even in cases where it is desired to secure the cloth 5 of the tie to the clip.

It is a further object of the invention to provide in a necktie of the described character in combination with a holder, clip or foundation, a cloth portion tied in an im- 10 proved manner for the purpose of varying the lengths of the free ends of the bow portion of the tie and also for varying the size of the knot at the center of the bow.

It is a further object of the invention to 15 provide an improved construction of material adapted to be used with non-reversible cloths when used in the manufacture of bow ties of this character.

Other objects of the invention will appear 20 from the following description which is directed to the preferred embodiment of the invention as set forth in the accompanying description and in reference to the drawings forming a part of the specification, the novel 25 features being particularly pointed out in the appended claims.

In the said drawings Fig. 1 is an outline or front elevation view of the substantially rigid metallic element of the clip or foundation 30 portion of my improved tie, and Fig. 2 is a top plan view of the same as shown in Fig. 1.

Fig. 3 is an outline or elevation view of the elastic metallic element of the tie clip or 35 foundation.

Fig. 4 is a view similar to Fig. 3 showing the elastic metallic element in the process of being covered by cloth and illustrating the manner of securing the covering thereto by 40 sewing or pasting it thereon, Fig. 5 being a sectional view on line 5—5 of Fig. 4 showing the detail and the manner of the application of the envelope or covering.

Fig. 6 is a view showing the rigid element 45 of Figs. 1 and 2 and the elastic element of Fig. 3 in their assembled relation and ready to have the cloth material of the tie attached thereto. In this view there is also shown in the assembly a special pin or pointed retaining device presenting one or more points upon which the cloth material of the tie may be impaled for better holding it in its adjusted position when tied on the clip or foundation.

Fig. 7 is a view illustrating the first step 55 in the application of the cloth material to the assembled clip or foundation made up of the parts of Figs. 1 and 3.

Fig. 8 illustrates the next step in the 60 foundation of the bow and Fig. 9 indicates the completed tie ready for attachment to the tabs of the collar of the wearer.

Fig. 10 is a view similar to Fig. 7, but 65 showing a modification in the manner of initially applying the cloth material from

which the bow is to be made to the clip or foundation for the purpose of varying the character of the intermediate knot position.

Figs. 11 and 12 are fragmentary views of one extremity of the flexible and rigid 70 metallic elements of a modified form of my invention and formed to have co-operating elevations and depressions for better attaching the clip or foundation to the tabs of the collar of a wearer, Fig. 12 being taken on line 12—12 of Fig. 11 looking in the direction of the arrows and showing a portion 75 of the collar tab held between the rigid and elastic members. In these views the portion of the flexible element of the clip which is deflected out of the common plane is also shown slotted for possible use in cases where it is desired to attach either a flexible envelope or parts of the tie proper to the flexible metallic element of the clip or foundation by 80 sewing. Figs. 13 and 14 are fragmentary detail views showing modifications of the outer extremities of the flexible metallic element of the clip or foundation of Fig. 3, whereby the cloth material after being tied 85 into a bow may be detachably secured thereto.

Fig. 15 is a fragmentary view of the middle or central portion of the assembled clip or foundation of Fig. 6 illustrating the 90 spaced points which project from the front of the foundation of the clip for positioning the cloth of the tie or for securing the cloth 95 of which the tie is to be formed when the same is made in two separated parts divided 100 approximately at the center of the strip.

The body of the rigid metallic element of the clip or foundation is designated generally by reference character *a*. The flexible element of the same by *b*. The rigid 105 element *a* will preferably be provided with strengthening center rib *a*¹ and with the usual laterally extending tongues *a*² designed to be used in attaching the elastic element *b* thereto in a well known manner by engaging 110 with the spaced notches *b*¹ at the center thereof. So much of the construction of the rigid metallic element *a* is common and well known and the present improvement upon 115 this element of the clip or foundation consists in providing the spaced lateral projections *a*³, of which there are four in number, two of which are spaced apart on each of the lateral edges of the element, each co-operating pair on the same side of the element having their outer extremities deflected toward each other but preferably not quite meeting so that there will be an interval or space between the inwardly projecting extremities 120 of each pair of the projections *a*³ through which the cloth material of the tie body will be inserted. However the same results may 125 be secured by continuing the material in the outer extremities of the projections *a*³ until they meet which makes a somewhat stronger 130

construction and in which event it will obviously be necessary to thread the cloth material of the tie through the openings thus formed. Because of the fact that the extremities of the cloth material are ordinarily much wider and contain more material than near the center where the knot is formed in the material, it is an advantage to be able to insert the cloth material laterally through the spaced openings between the projecting members a^3 , as illustrated.

When the rigid member of the clip is formed as illustrated in Figs. 1 and 2 and is assembled with the flexible element of Fig. 3 either with or without the cloth covering or envelope illustrated in Figs. 4 and 5, which is optional, the cloth of the bow designated generally by reference character c may be applied as illustrated in Fig. 7 so that it will be attached at a point about midway of its extremities to the clip or foundation and held against movement longitudinally of the clip or foundation by means of the integral retaining devices or projections a^3 . The tie is then ready to have the bow completed in the manner depicted in Figs. 8 and 9, the resulting knot being of the double bow variety and produced by the operator taking one of the free ends of the cloth material bringing it around at right angles on the side of the clip or foundation which is exposed in Fig. 7 and then wrapping the free end or portion of the material in a loop around the center of the clip or foundation and the folded material of the cloth and finally passing the same under the thus formed central band in the form of a loop and drawing the same taut resulting in the completed bow of Fig. 9. It is sometimes desirable that the central or encircling band portion of a bow tie of the style of Fig. 9 shall be more or less full or prominent and this result may be secured by the special means of inserting the material on the clip or foundation illustrated in Fig. 10 by which the material is given one complete loop around the central portion of the assembled elastic and rigid members of the clip and then has its free end extend from the retaining or projecting members a^3 in the same relative positions as they do in Fig. 9, although obviously, somewhat shortened, the correct position of these parts being illustrated in Fig. 10, after which the completion of the tying of the bow will proceed exactly as in the case of the form of Fig. 7 as illustrated in Figs. 8 and 9.

After the cloth material of the tie is formed as in Fig. 9 it is sometimes found that there is a tendency for the free ends of the bow to sag or twist in relation to the clip or foundation and it has been common heretofore to sew the looped ends of the bow near their outer extremities to the elastic spring member b of the foundation. As the

present invention is directed to a bow which can be tied by the wearer as distinguished from what is known as the made up and permanent variety of bow tie, it is desirable that permanent means as stitching be dispensed with in attaching the free ends of the bow to the elastic metallic element of the clip or foundation. To secure this result I provide a special construction of the outer extremities of the elastic metallic element 75 of the foundation as indicated by reference characters d and e , Figs. 13 and 14. In Fig. 13 the outer extremity of the elastic element d is provided with a double slit having the central tongue d^1 with a sharpened 80 projecting element d^2 formed out of the body thereof. There will be sufficient elasticity in the tongue member d^1 so that the wearer of the tie upon tying the cloth material of the bow may deflect the tongue member d^1 out of the plane of the body of the spring member d and push the cloth of the bow so that a portion thereof will be held between the tongue d^1 and the body d of the spring, this part of the cloth at the 85 same time being impaled by the projection d^2 which will prevent the cloth from slipping until the wearer shall desire to release it to untie the bow, thus making the same a detachable means of securing the cloth 90 of the bow thereto. In Fig. 14 the same result is accomplished by omitting the impaling member d^2 from the tongue d^1 but forming the latter with a slight sinus or bend out of the plane of the body of the 95 spring e so that the pin h may be inserted thereunder and at the same time passed through the material of the tie thus holding the parts together. In Fig. 11 I show an 100 elevation view of the clip or foundation with the elastic element thereof here indicated by reference character m provided with a portion indicated at m^1 being of a concavo-convex shape and formed out of the plane 105 of the body portion and slit. There is also shown in Fig. 12 a section indicating the manner in which the cloth material of the collar tabs, especially when the device is used with a soft collar, will be impinged between the two metallic elements of the clip 110 or foundation, the cloth of the collar tab being shown in section in Fig. 12 and indicated by reference character n while the rigid element indicated by reference character k will be formed with a co-operating 115 concavo-convex portion indicated at k^1 but never slotted, as there is no necessity of ever placing an envelope or covering over the rigid member of the clip or foundation.

In Figs. 4 and 5 I show an important feature of the invention which resides in the manner of placing an envelope upon the flexible or elastic element b of the clip or foundation. The cloth covering indicated generally by reference character r will be 120

cut preferably rectangular in form and will have both of its end portions r^1 and r^2 projecting beyond the extremities of the flexible metallic member b pasted flat over the end 5 thereof as illustrated in Fig. 4. One of the longitudinal side edges as indicated at r^3 will next be folded flat upon the top of the same and over the previously folded end flaps r^1 and r^2 . Finally the remaining side 10 flap indicated in Figs. 4 and 5 by reference character r^4 will be folded over and pasted upon the flap r^3 and covering any exposed portion of the spring member b . Heretofore it has been the custom to stitch an 15 envelope of cloth around the extremities of the spring element b and this operation has been expensive. It is found that considerable economies may be secured by pasting the envelopes in the manner herein described and that the envelopes thus secured 20 will be sufficiently permanent for all practical purposes.

A tie made in accordance with the invention with respect to the metallic clip 25 or foundation and when tied in the manner herein described presents many qualities to be desired, being capable of manipulation by the wearer it avoids the objectionable uniformity of factory tied materials and 30 enables the wearer to exercise a certain amount of individuality in the use of neck-wear of this character. At the same time the bow is much more economical than with ties of this character where it has been the 35 custom to provide in connection with the material part a collar and encircling band which results in a great waste of materials of an expensive character that never show 40 nor perform any function except to assist in retaining the bow in position upon the collar or collar band. Obviously, a clip or foundation of this character may be repeatedly used with cloth materials and the latter may be replenished whenever they 45 become soiled or worn without necessitating the destruction or abandonment of the clip or foundation. Furthermore the improved retaining means for the bow provided in the special construction of the clip or foun- 50 dation makes possible the retention of the bow in its proper shape and position after it is tied and until the wearer desires to remove same from the clip or foundation.

The modification of the clip or foundation shown in Figs. 6 and 15 comprising the 55 spaced perforations indicated by reference characters 30, 31 of Fig. 15 formed in the elastic member b of the clip permits the insertion of a U-shaped pin through these 60 openings, the legs of which are indicated by reference characters 32 and 33 are pointed and extend outwardly from the concave edge of the elastic member of the clip. It results that in the tying of the bow the 65 cloth material of the bow adjacent the knot

will become impaled upon these points 32, 33, resulting in firmly anchoring the bow of the tie to the foundation or clip. This construction is also an advantage where it is desired to use a cloth bow made of 70 two different colors or designs of cloth in which event the tie proper comprising a strip such as indicated by reference character c in Fig. 7 may be formed of two separate pieces such as would be produced for 75 example by cutting the material of the cloth portions c of Fig. 7 along the median line between the parallel sides of the elastic clip member b of Fig. 7. This obviously, 80 would sever the cloth material c into two portions and when such is the case before the cloth material could be tied it would be necessary to sew or otherwise put it together, but such a result could be avoided and yet the material satisfactorily tied by 85 the use of the impaling points 32, 33 since the free ends of the material on being inserted in the retaining loops of the clip or foundation might be lapped and impaled on the points 32, 33 and held as firmly for 90 purposes of tying as though the segments of the strip were formed integrally. The U-shaped member having the points 32, 33 may advantageously have a slight reverse 95 curve in the body portion thereof between the parallel pointed extremities 32, 33 and it is an important feature of this combination that the connecting body member of the pins 32, 33 will lie within and be supported in the hollow or concave side of the 100 rib part a^1 of the rigid metallic member a of the clip or foundation.

It will be seen from the view of the spring member b in Fig. 6 that the ends or extremities thereof are rather abruptly re- 105 versely curved as indicated at g . This is an important feature of my invention making it always possible to satisfactorily cover the ends of the spring b by the pasting process or method herein disclosed and ren- 110 dering such covering method practicable for the reason that I find when the ends g of the spring b are not reversely curved as, indicated in Fig. 6 the covering on the ends 115 will not last any length of time whether sewed or pasted because of the wear incident friction of the fingers of the wearer thereon in adjusting the tie.

Another feature of the invention embraced in the envelope or covering of the spring 120 member b as illustrated in Fig. 4 that is important in practical manufacture results from the tendency of portions of the cloth envelope at the extremities of the spring b to protrude beyond the metal of the spring 125 a slight distance and sufficient to permit a needle in sewing or stitching the cloth of the tie bow thereto when the stitching method is employed in securing the spring ends to the tie body.

I claim:

1. In a neck tie the combination with a body portion of cloth and a metallic foundation comprising a rigid member and an elastic spring member, means for securing the said rigid and elastic spring members together, means for retaining the body portion of the tie in position on the foundation, and means for detachably connecting the free extremities of the tie body to the free ends of the elastic member of the foundation.
2. In a neck tie the combination with a body portion of cloth of a metallic foundation comprising a substantially rigid member and a flexible metallic member, of means for securing said members together, there being separated openings in the body portion of the flexible metallic member and impaling devices having pointed projections arranged to extend through said openings in the body part of the flexible metallic member on the side thereof remote from the substantially rigid metallic member, whereby to anchor the cloth material of the tie in position on said clip or foundation.
3. In a neck tie the combination with a foundation comprising a flexible metallic member and a substantially rigid member, means for attaching the said members together, the said flexible metallic member being provided adjacent the intermediate portions thereof with a perforation and a pointed member anchored on the side of the flexible metallic member adjacent the rigid member and having a pointed portion there-

of projecting through the said perforation to the opposite side of the flexible metallic member upon which the cloth of the neck tie to be tied thereon is adapted to be impaled when the tie is adjusted in its normal position on the clip.

4. In a neck tie the combination with a foundation for neck ties comprising a substantially rigid metallic member and a flexible member, means for attaching the same together, there being a plurality of spaced perforations in the flexible metallic member and a U-shaped pin having a plurality of spaced pointed branches projecting from the side of the flexible metallic member adjacent the rigid member through said perforations in the flexible member and upon which the cloth material of the tie is adapted to be impaled to assist in holding the tie in its adjusted position on the foundation.

5. In a necktie, the combination with a cloth body portion of a metallic foundation comprising a substantially rigid member and a metallic elastic member, means for securing the said parts of the foundation together, and means for securing the said foundation firmly to the tabs of a collar, the said last named means comprising cooperating concavo-convex portions in the rigid member and the elastic member.

In testimony whereof I have signed my name to this specification, on this 21st day of February, A. D. 1920.

JOHN A. SODERSTROM.
